THERMIONIC VALVE ELEMENT ASSEMBLY

Harry Diggle, Harrow-on-the-Hill, England, assignor to Hivac Limited, Harrow-on-the-Hill, England, a British company

Application March 18, 1947, Serial No. 735,444
In Great Britain March 21, 1946

7 Claims. (Cl. 250—27.5)

1

The present invention concerns improvements in or relating to the manufacture of thermionic valves.

In manufacturing thermionic valves, particularly small type miniature or midget valves it is usual to space the electrodes by supports therefor passing through holes in spaced mica discs. This has the disadvantage that as the demand for smaller and smaller valves and the requirement for valves with more and more electrodes grow, the difficulties increase of getting sufficient holes in the space available for assembling the various grids and getting the filament in position.

An object of the present invention is to provide a method of construction and assembly whereby these difficulties are overcome in a simple manner.

According to one feature of the present invention all the electrodes are substantially planar.

According to another feature of the present invention the electrodes are assembled in a stacking process with suitable spacers such as mica stampings to space them the desired distance apart.

According to a third feature of the invention an electrode assembly comprises a flat filament mounting, and one or more flat grids between the filament and an anode, said anode having extensions arranged to embrace the assembly so as to hold it together.

According to a fourth feature an electrode assembly comprises one or more flat grids arranged on each side of the filament and anodes are arranged on the outer sides of the grids having extensions arranged to embrace the assembly so as to hold it together.

According to a fifth feature of the invention the electrodes are of V- or U-shape and are assembled by a simple stacking process one with in the other with interleaved insulating pieces for spacing and insulating purposes where necessary.

The elements of a valve essentially consist of a filament, one or more grids and one or more anodes.

In one form the filament is mounted across an opening in a flat frame which may take the form of a bridge-piece of mica or like material so that the filament and support lie substantially in a plane. The grid or grids are also planar conveniently being constructed as described in my co-pending application No. 735,445. The anodes may be plain rectangular stampings, while separating pieces may be provided consisting of

2

rectangular mica frames, that is to say rectangular stampings of mica with rectangular holes.

The grids and the anodes may be provided with lugs situated differently from each element. To assemble the electrode structure all that is necessary is to insert the elements one by one in a jig with interposed separating pieces just as may be desired. For instance, for a simple three electrode valve one would insert firstly an anode element, a separator, a grid element, the filament, a separator, a second grid element, a separator and a second anode element. Appropriate tags would be welded respectively to the lugs of the anodes and the grids. The anode tags joining the two anodes would serve to hold the assembly in place although other means could readily be provided so that the assembly could be secured in position in a tube.

It will be readily appreciated that for envelopes requiring two valve systems with a common filament the combination might be similar to that just described except that separate terminals would be required for the two anode elements and the two grid elements. For a pentode or tetrode valve all that is necessary is to add the appropriate grids or other electrodes with separators in the appropriate place. It is not necessary however that all the elements should be flat, the grids consisting of spaced wires on a rectangular frame stamping may be bent to have a U-shaped section into which the filament may be slipped sideways or vice versa. The supports in such a case might be interposed bridge separators or spaced mica discs as hitherto but in this case, for instance where a number of grids were required the supports not requiring to be on a line can be suitably separated.

The assembly in an envelope may follow any known method, for instance a glass pinch for gripping the tags may be sealed as a re-entrant into a glass envelope or the mica distance pieces may be provided with toothed edges so as to form a glass fit into the envelope which could be pinched on to the flexible leads extending from the electrodes or the respective tags may be sealed in a glass button which is in turn sealed into the end of the glass envelope.

A preferred embodiment of the invention will be described with reference to the accompanying drawings which show the embodiment on an enlarged side.

Figure 1 is an exploded view of the electrode assembly.

Figure 2 is a side elevation of the electrode assembly mounted in its glass envelope.

Figure 3 is a front elevation of the electrode assembly mounted in its glass envelope.

Fig. 4 is an exploded view of the electrode assembly of a modification of the invention.

Fig. 5 is a side elevation of the electrode assembly of Fig. 4 mounted in its glass envelope.

Fig. 6 is a front elevation of the electrode assembly of Fig. 4 mounted in its glass envelope.

Referring first to Figs. 1, 2 and 3 filament 1 is mounted across an opening in a flat mica frame plate 2: it is held at the bottom by an extension strip 3 on a nickel tag 4 which is attached to the frame plate 2 by being threaded through a pair of slots therein and flattened over at each end. To the tag 4 is attached one of the filament leads 5 (see Figure 3). At the top the filament is attached to a spring 6 which, in turn, is attached to a nickel tag 7 which is held on the mica frame 2 by being threaded through a pair of slots therein and flattened over at each end as in the case of the tag 4. The tag 7 also supports a frame 8 for the getter material and is connected to the second filament lead 9. A further description of the filament mounting will be found in Goulding's application No. 736,731, which issued on February 7, 1950, as Patent No. 2,496,530.

On either side the filament are mica frames 10. These frames are arranged to cover only about half of the filament mounting but so that the filament 1 is centrally disposed down the aperture in the frame.

Next on each side of the filament mounting are placed grids 11 the construction of which is described in detail in my co-pending application No. 735,445. These are lead out to the grid leads 12, 13 (see Figure 3).

Outside the grids are placed further mica frames 14 and finally nickel anodes 15 with extension arms 16 and connected to the leads 17 and 18. On one side the extension arms pass through slots 19 in the mica plate 2. The ends of the extension arms 16 are bent down over the corresponding mica frame 14 at the opposite side of the filament mounting to hold the assembly secure.

The assembly is enclosed in its glass envelope 20 in the manner usual in the art.

Referring now to Figs. 4, 5 and 6, in which corresponding parts are identified by the same reference numerals as in Figs. 1, 2 and 3, a filament 1 is mounted across an opening in a flat mica plate 2 of similar construction to that already described in connection with Fig. 1.

On either side of the plate 2 and adjacent the slots 19 are placed mica strips 21, arranged so as to leave the filament exposed at either side. A U-shaped grid 22 comprising a metal frame with attached transverse wires and with a connecting lug 25 partially embraces the plate 2, the curved portion of the U-shape surrounding the filament 1 while the arms of the U are spaced away from the plate 2 by the engagement of the edges of the grid frame which lie along the free-ends of the two limbs of the U-shaped part, with the strips 21.

Outside this grid are placed two further mica strips 21, one at either side of the arms of the U and overlapping the first pair of strips 21. Finally, a U-shaped anode 23 with a connecting lug 26, and four further lugs 24, whose purpose will become apparent later, is placed over the grid so that the base of the U-shaped part embraces the base of the U-shaped grid without touching

it, while the side limbs of the U-shaped part overlap the arms of the U-shaped grid, and are spaced away therefrom by the second pair of mica strips 21. The lugs 24 are previously bent over so as to

5 pass through the slots 19 in plate 2 and are then bent again so as to retain the whole assembly together in a manner analogous to that of Figs. 1, 2 and 3. Connecting wires 27, 28 are spot welded to the grid lug 25 and anode lug 26 respectively 10 to form the external connections; the filament connecting wires are shown as before at 5 and 9.

The assembly is then enclosed in its evacuated glass envelope 20 in the manner usual in the art.

Obviously similar methods could apply to the 15 construction of multigrid valves while where a plurality of valve systems are employed, these may have a common cathode and be arranged on opposite sides of the filament or the various systems could be separated in any manner known in the art provided the separator was so shaped as to permit of it being stacked.

Other insulating materials such as ceramics 20 may replace mica.

I claim:

25 1. An electrode assembly for thermionic valves in which the electrodes other than the filament are of substantially U-shape and are stacked one within the other with interleaved insulating pieces for spacing and insulating purposes, the assembly being held together by bent over extensions on the anode, which pass through slots in a filament mounting centrally inserted in the assembly.

30 2. A method of constructing a thermionic valve 35 which comprises the steps of forming each of the component electrodes as elements of planar sheet form including two anode-forming elements as flat metal plates, providing extension lugs projecting from one pair of opposite side edges of each of said anode plates and forming the cathode element to include a flat sheet of insulating material of larger size than that of the other electrodes, and providing apertures therein through 40 which at least some of said extension lugs are passed, assembling said electrodes by a stacking process of first laying an anode plate, then laying the remaining electrodes thereon in register and one upon the other in appropriate order and terminating with the other anode electrode with interleaved spacing frames of sheet insulating material whose thickness dimension determines the related inter-electrode spacing distance, and then securing the stacked assembly as a unitary structure by bending over the extremities of each of 45 said extension lugs on to the opposite side of the stack of electrodes so as to grip the thickness dimension of the stack.

50 3. An electrode assembly for a thermionic valve comprising a filament mounting including a flat sheet of insulating material having an opening therein and a filament wire spanning such aperture, a spacing frame of sheet insulating material disposed in contact with one side of said sheet of 55 said filament mounting and with the frame aperture aligned with said opening, a grid electrode in the form of a sheet metal frame with transversely directed grid wires disposed in contact with the opposite surface of said spacing frame and with its aperture in alignment with that of said frame, a further spacing frame of sheet insulating material disposed in contact with the other side of said grid electrode and with its aperture in alignment with that of said first spacing frame, an anode electrode in the form of a flat metal sheet disposed in contact with the opposite

surface of said further spacing frame, and integral extension lugs on opposite sides of said anode plate, said extension lugs being bent to lie adjacent the side edges of the assembled stack of electrodes and spacing frames and having their free ends bent over on to a surface of the stack on the side of the filament mounting which is opposite to that of the anode so as to grip and hold the assembly in clamped relationship.

4. An electrode assembly for a thermionic valve comprising a plurality of electrodes all of planar sheet form and including two anode-forming elements each constituted by flat metal plates and a filament mounting constituted by a flat sheet of insulating material having an opening therein spanned by a filament wire, a plurality of spacing frames of sheet insulating material, said electrodes being arranged in face-to-face relationship on each side of said filament mounting and with said spacing frames interleaved between adjacent electrodes to effect electrode spacing means and with one of said anodes as the outermost electrode on each side of said filament mounting, and extension lugs on each of said anodes, said lugs being bent to extend along the thickness dimension of the assembled stack of electrodes and spacing frame and having their free ends bent over on to the opposite side of the stack to form mechanical clamping means by which the parts are held secured in position.

5. An electrode assembly for a thermionic valve comprising a filament mounting of planar form and including two flat sheets of insulating material placed face-to-face and having aligned openings therein and with a filament wire located in between said sheets and spanning said openings, two anode elements each in the form of a flat metal plate and disposed one at each side of said filament mounting in parallel relationship therewith, at least one pair of grid elements each in the form of a sheet metal frame having spaced wires spanning the frame aperture and located one of each pair at each side of said filament mounting intermediate the latter and the adjacent anode plate and parallel therewith, spacing frames of sheet insulating material disposed in between each of said grid and anode elements and said filament mounting with the thickness of said insulating sheet determining the inter-electrode spacing distances and integral extension lugs on each of said anode elements, said lugs being disposed in mutually staggered relationship, and being bent to extend along the thickness dimension of the assembled stack of electrode elements and interleaved spacing frames and having their free ends bent over onto the outermost surface of spacing frame between the anode and adjacent grid element on the opposite side of the filament mounting from that at which the integral anode plate is disposed so as to grip and secure the intervening electrode elements and spacing frames therebetween, the anode plates each being of restricted size so as not to contact the bent-over ends of the extension lugs of the opposite anode.

6. An electrode assembly for a thermionic valve of the type having a plurality of electrode elements each of planar form and comprising an anode element in the form of a flat metal sheet, a filament mounting comprising a flat sheet of insulating material having an opening therein and a filament wire spanning said opening, and a plurality of apertured frames of sheet insulating material, said electrodes being disposed in stacked face-to-face relationship with said frames disposed at least one between each adjacent pair of electrodes and forming the sole inter-electrode spacing means, said anode element being provided with extension lugs integral with said flat metal sheet, said lugs projecting from at least one pair of opposite edge regions of said sheet and being directed along the thickness edges of the stack and having their free ends bent over on to the opposite side of the electrode stack to form means for gripping the thickness dimension of such stack and said filament mounting sheet being of greater dimension on at least one side of said assembled other electrodes and having apertures at that side for the passage therethrough of said extension lugs of said anode elements.
7. An electrode assembly for a thermionic valve of the type comprising a plurality of electrode elements each of planar form, which includes an anode element consisting of a flat metal sheet, and a plurality of apertured frames of sheet insulating material said electrodes being disposed in stacked face-to-face relationship with said frames disposed at least one between each adjacent pair of electrode elements and forming the sole inter-electrode spacing means, said anode element having integral extension lugs projecting from one pair of opposite side edge regions of the sheet and having its dimension parallel with such side edges less than the similar dimension of the aperture of the adjacent spacing frame, said extension lugs being directed along the thickness edges of the stack and having their free ends bent over on to the opposite side of the electrode stack to form means for mechanically gripping the thickness dimension of the stack.
